tion of New York

Application March 19, 1951, Serial No. 14,537

Term of patent 14 years

(Cl. D48—24)

To all whom it may concern:

Be it known that I, Sidney Schwartz, a citizen of the United States and resident of New York, in the county of New York, State of New York, have invented a new, original and ornamental Design for a Combined Key Chain and Flashlight of which the following is a specification, reference being had to the accompanying drawing, forming a part thereof, and of which

Fig. 1 is a perspective view showing the top, front, and one side of a combined key chain and flashlight embodying my new design, with the cover in open position.

Fig. 2 is a perspective view showing the top, rear and the other side of my design, with the cover in closed position.

Fig. 3 is a top plan view of the combined key chain and flashlight shown in Fig. 2, and

Fig. 4 is a bottom view thereof with the chain in a displaced position.

The drawing is shaded to show contrasting appearance.

I claim:

The ornamental design for a combined key chain and flashlight, as shown and described.

SIDNEY SCHWARTZ.
